(57) CLAIM

The ornamental design for a free standing grappling bag with tripod base, as shown and described.

DESCRIPTION

FIG. 1 is a perspective view of the free standing grappling bag with tripod base showing our new design;

FIG. 2 is a front view thereof;

FIG. 3 is a back view thereof;

FIG. 4 is a right side view thereof, where the left side view is a mirror image of the right side view;

FIG. 5 is a top view thereof; and,

FIG. 6 is a bottom view thereof.

1 Claim, 5 Drawing Sheets
